MECHANISM FOR FEEDING BLANKS

Lysle J. Pulse, Muscatine, Iowa, assignor to Hawkeye Pearl Button Company, Muscatine, Iowa, a corporation of Iowa

Application October 15, 1936, Serial No. 105,793

14 Claims. (Cl. 79—17)

This invention is a novel feeder, particularly adapted for use in connection with button making machines of the type disclosed in Barry Patent No. 766,014, dated July 26, 1904, in which an endless series of button holding chucks are moved in an orbital path into a feeding position where the chucks are successively supplied with blanks and subsequently moved under a grinding wheel; and the principal objects of the invention are to provide an automatic mechanism for such or similar machines involving a direct and positive drive for feeding blanks into the chucks or the like at a desired point in the orbital path of movement of the chucks; also to automatically position the chucks directly below the feeding point to insure that a blank will be properly deposited in the chuck.

I will explain the invention with reference to the accompanying drawings which illustrate one practical embodiment thereof to enable others familiar with the art to adopt and use the same; and will summarize in the claims the novel features of construction, and novel combinations of parts, for which protection is desired.

25 In said drawings:—

Fig. 1 is a plan view of the feeding and chuck positioning mechanism illustrating the drive therefor and its relation to the endless series of chucks of a button machine. Fig. 2 is a vertical section through the mechanism on the line 2—2, Fig. 1. Fig. 3 is a vertical section through the mechanism on the line 3—3, Fig. 1; and Figs. 4 and 5 are perspective details.

The conventional automatic button machine shown in the drawings includes an endless series of button holding chucks A carried in rotatable spindles B loosely mounted in chain housings C pivotally connected together as at D to form an endless chain of said housings C running around notched wheels E—F, one wheel E being mounted on a drive shaft G carrying a worm wheel H driven in the direction of the arrow (Fig. 1) by worm J on a shaft K driven as by a pulley L in the usual manner, while the other wheel F is loose on its shaft M. Spindles B usually have a loose fit within housings C permitting considerable play therein, a space N (Figs. 1 and 3) being provided between the spindles and housings. The lower ends of the spindles carry balls 50 P moving upon cams Q in the usual manner, the above construction forming no part of my present invention.

The feeding mechanism shown consists of a stationary plate 1, preferably of circular shape, provided with an upstanding flange 1a at its

periphery, said plate 1 having an axial opening 1b for a vertical shaft 2 which passes through a collar 3 which supports plate 1, the collar 3 being secured to the underside of plate 1 and making a telescopic engagement with a bearing 4 for shaft 2 supported upon a bracket 5a on a cross member 5 extending between uprights R—R of the button machine. The lower end of shaft 2 is journaled in a bearing bracket 4x mounted upon a lower cross member 5x likewise mounted 10 between the uprights R—R. A set screw 6 is provided in the collar 3 for adjusting the vertical elevation of plate 1 on cross member 5, so that the plate 1 is disposed slightly above the tops of chucks A with a portion of its periphery overlapping the feeding point, such as S in Fig. 1, in the orbital path of chucks A.

In the plate 1 directly over the feeding point S is an arcuate slot 1c, one end of which registers with the exact position of the chuck A at 20 the feeding point S, the slot being elongated in the direction of movement of the chucks beyond the feeding point. Slot 1c is of width sufficient to permit a button blank to drop through the slot 1c into the top of the underlying chuck A. 25

Rotatably mounted upon the plate 1 and in contact therewith, is a plate 7 having its periphery terminating within the upstanding flange 1a, said plate 7 being secured by screws to the lower end of a sleeve 8 adjustably mounted by means of 30 a set screw 8a on the upper end of shaft 2, whereby as the shaft 2 is rotated, plate 7 will rotate therewith in the direction of the arrow, Fig. 1.

Shaft 2 is rotated with shaft G, but in the 35 opposite direction, shaft 2 carrying a worm gear 9 bearing upon the top of member 4x (Fig. 2) and meshing with a worm 10 on the shaft K; and as the worms 10 and J, and the worm gears 9 and H are of the same size, the shaft 2 is rotated at the same speed, and therefore in synchronization with the rotation of the chuck driving wheels E—F, and the plate 7 moves in the same direction as the chucks A past the feeding point S.

In the rotatable plate 7 adjacent its periphery 45 are a series of holes 7a, ten being shown, disposed on a pitch diameter the same as that of the arcuate slot 1c in the fixed plate 1, the holes 7a being spaced equal distances apart, and the center-to-center distance between holes being 50 equal to the pitch of the button chucks A, whereby as the button chucks A travel past the feeding point S, the plate 7 will be revolved in perfect time therewith so that the holes 7a in the revolving plate which carry the button blanks, register 55.

with the chucks through slot 1c at feeding point S (Fig. 1).

The button blanks are placed in the hopper formed by plate 7 and flanges 1a, and the button making machine started, causing the chuck drive wheels E-F to rotate in the direction of the arrow, Fig. 1. Each hole 1a in the revolving plate 7 is filled with a blank as the plate revolves in the direction of the arrow, Fig. 1, and as the blanks are carried around to feeding position S they drop through slot 1c in stationary plate 1 and into the underlying button chucks A which are then in position to receive the blanks.

An important feature of my machine is the means for controlling the buttons in the hopper formed by the plate 7 and flange 1a. The revolving plate 7 rotates in a clockwise direction as shown by the arrow, Fig. 1, and during rotation the button blanks are carried around with the plate until they come in contact with a baffle plate 11, which is fixed and so inclined as to cause the blanks to be shifted laterally towards the periphery of plate 7 into position to insure filling the holes 1a which receive them, one blank at a time. As shown, baffle plate 11 is disposed substantially radially, and has a flange 11a at its outer end which is secured to the flange 1a, its inner end contacting the rotating collar 8. In the outer lower corner of baffle 11 is an opening 11b (Fig. 4) above the pitch circle of the series of holes 1a in plate 7, the opening 11b permitting surplus blanks to pass beyond the baffle 11.

Between the baffle 11 and the feeding point S is a bracket 12 having a flange 12a (Fig. 4) mounted on flange 1a, said bracket 12 carrying a pair of guide plates, 13 and 14, for the purpose of clearing the periphery of plate 7 of loose blanks, except those in the holes 1a, immediately before reaching the feeding point S. Guide plates 13 and 14 have their outer ends contacting with flange 1a so as to deflect the blanks which pass baffle plate 11 inwardly toward the center of plate 7 so that these blanks will be carried on around with plate 7 and subsequently forced toward the periphery of plate 7 as they again contact with baffle plate 11.

Thus as each blank reaches the feeding point S the periphery of plate 7 is cleared of loose blanks to insure that only one blank will be deposited at a time in the underlying chuck A positioned at a time in the underlying chuck A through slot 1c in fixed plate 1; and as the plate 7 is rotated the loose blanks in the hopper are subsequently forced to the periphery of the plate 7 by baffle 11 so as to fill the holes 1a to ensure that a blank will always be deposited in each chuck A at the proper moment. The elongation of slot 1c, in plate 1 in the direction of travel of the chucks is an added safety feature to ensure the proper depositing of blanks in the chucks at the feeding point S, for in event a blank should initially wedge or become stuck in the slot 1c or hole 1a at the feeding point, the elongation of the slot 1c will somewhat increase the time during which the blank may drop into the moving chuck from the synchronously moving plate 1.

I also provide means for automatically properly positioning the chucks A at the feeding point S, due to the play of the spindles B in the chain housings C occasioned by the spaces N (Figs. 1 and 3), it being found that in practice the spindles which carry the button chucks were not always in correct alignment to receive the blanks at feeding point S. A guide member 16, mounted on a fixed upright 17, is horizontally positioned so as to be engaged by the upper ends of spindles

B as the latter advance to and slightly beyond the feeding point S, the guide 16 engaging the inner peripheries of the spindles and preventing same from being deflected laterally inwardly away from the position of correct alignment with the registering holes 1a and slot 1c at feeding point S. Cooperating with guide 16 is a disk 18 carried by a collar 19 adjustably mounted by means of a set screw 19a on the shaft 2 below the cross member 5, the disk 18 thereby rotating in unison with the plate 7 of the feeding mechanism. Disk 18 is provided with semi-circular notches 18a concentric with the holes 1a in plate 7 as clearly indicated in Fig. 1, said notches 18a being of radius to suit the diameter of the spindles B, the disk 18 being so positioned on shaft 2 that the notches will embrace the spindles B at the feeding point S and hold the spindles in correct position longitudinally and laterally of the run of the series of spindles so that the chucks will always be in alignment with a hole 1a in plate 7 through slot 1c at the feeding point. In event a spindle when approaching the feeding point S should be "lagging" in its chain housing C, the related notch 18a in disk 18 will, by cooperation with guide 16, cause the spindle to "advance" in its housing as the notch 18a embraces the spindle, thereby adjusting same to correct feeding position at point S. If the spindle is too far ahead the disk 18 will act to retard same at the feeding point S in a similar manner. Thus by the use of guide 16 and disk 18 the spindles B may be positioned to very close limits both longitudinally and laterally of the direction of travel of the chain, at the feeding point S.

In operation

When the button machine is in operation plate 7 is rotated synchronously with and in the same direction as the movement of the underlying run of chucks A so that a hole 1a of plate 7 registers with each chuck through slot 1c of plate 1 at the feeding point S (Fig. 1), the chucks A being properly positioned beneath the feeding point S in their chain housings C by contact with the lateral adjusting guide 16 and the longitudinal adjusting disk 18. The button blanks placed in the hopper formed by plates 7 and flange 1a, are carried around in the direction of the arrow, Fig. 1, by plate 7, and any blanks which do not initially fall into the holes 1a will contact baffle plate 11 which shifts the loose blanks outwardly towards the periphery of plate 7 into the path of movement of the holes 1a thus insuring that all holes 1a will receive a blank. Any surplus blanks at the periphery of plate 7 pass through hole 11b of baffle 11 as plate 7 rotates, and are deflected inwardly from the periphery of plate 7 by guides 13 and 14 thus clearing the periphery of loose blanks, except those in holes 1a, immediately before reaching the feeding point S. Thus in my mechanism only one blank is deposited at a time in each chuck A through slot 1a as the chucks reach the feeding point S.

As plate 1 is adjustable on the cross member 5, and rotatable plate 7 and guide disk 18 are adjustable on shaft 2, the feeding and chuck positioning mechanism may be readily adapted to suit various types and makes of button machines; and I do not limit my invention to use with the type illustrated in the drawings; nor do I limit my invention to the exact details shown, for obviously changes may be made therein within the scope of the claims.

I claim:—

1. Mechanism for feeding blanks comprising a

- fixed member having a discharge opening constituting the feeding point; a second member movably mounted on the fixed member and supporting the blanks and having series of blank receiving holes therein adapted to register with the discharge opening; means overlying the second member for moving the second member; means for initially shifting the blanks on the second member towards the series of holes to fill the latter as same advance towards the feeding point; and means overlying the second member and interposed between the blank shifting means and the feeding point for clearing the second member of loose blanks adjacent the feeding point.

10. In combination with a machine having a series of blank receiving chucks and having means for moving same in an orbital path; mechanism for automatically delivering blanks to the chucks at a feeding point in their orbital path comprising a blank receiving hopper overlying the path of the chucks and having a discharge opening therein at the feeding point; a rotatable plate in the bottom of the hopper having a series of blank receiving holes therein adapted to register with the discharge opening; means for rotating the plate in synchronism with the movement of the chucks whereby a hole is brought into register with the discharge opening as each chuck enters the feeding point; and mechanism for aligning the chucks with the discharge opening when reaching the feeding point comprising a fixed member engaging the chucks opposite the feeding point to position same laterally with respect to the orbital path of the series; a movable member engaging the chucks opposite the feeding point to position same longitudinally with respect to the said orbital path; and means for driving the movable member in synchronism with the delivery mechanism.

15. 2. In mechanism as set forth in claim 1, said blank shifting means comprising a fixed baffle on the fixed member inclined with respect to the axis of movement of the second member so as to shift the blanks towards the holes, said baffle having an opening in its lower edge above the holes for the passage therethrough of surplus blanks.

20. 3. In mechanism as set forth in claim 1, said clearing means comprising a guide on the fixed member inclined with respect to the axis of movement of the second member so as to shift the loose blanks towards the center of the second member.

25. 4. In mechanism as set forth in claim 1, said discharge opening in the fixed member being substantially elongated beyond the feeding point in the direction of movement of the second member to increase the time in which the blanks may be discharged at the feeding point.

30. 5. Mechanism for feeding blanks comprising a blank receiving hopper having a bottom plate provided with a discharge opening constituting the feeding point; a rotatable plate in the bottom of the hopper having a series of blank receiving holes therein disposed on a pitch circle of same radius as that of the discharge opening; means for rotating the rotatable plate whereby the holes thereof are successively brought into register with the discharge opening; means overlying the plate for initially shifting the blanks in the hopper into position to fill the holes of the rotatable plate as same advance towards the feeding point; and means overlying the plate and interposed between the shifting means and the feeding point for clearing the rotatable plate of loose blanks adjacent the feeding point.

35. 6. In mechanism as set forth in claim 5, said blank shifting means comprising a fixed baffle in the hopper inclined so as to shift the blanks towards the pitch circle of the holes, said baffle having an opening in its lower edge above the holes for the passage therethrough of surplus blanks.

40. 7. In mechanism as set forth in claim 5, said clearing means comprising a pair of fixer guides extending inwardly from the sides of the hopper disposed over the pitch circle and inclined so as to shift the loose blanks towards the center of the hopper.

45. 8. In mechanism as set forth in claim 5, said discharge opening in the bottom being substantially elongated beyond the feeding point in the direction of rotation of the rotatable member to increase the time in which the blanks may be discharged at the feeding point.

50. 9. In combination with a machine having a series of blank holding chucks and having means for moving same in an orbital path; mechanism for automatically delivering blanks to the chucks at a feeding point in their orbital path; and mechanism for aligning the chucks with the delivery mechanism at the feeding point comprising a fixed member engaging the chucks opposite the feeding point to position same laterally with respect to the orbital path of the series; a movable member engaging the chucks opposite the feeding point to position same longitudinally with respect to the said orbital path; and means for driving the movable member in synchronism with the delivery mechanism.

55. 10. In combination with a machine having a series of blank receiving chucks and having means for moving same in an orbital path; mechanism for automatically delivering blanks to the chucks at a feeding point in their orbital path comprising a blank receiving hopper overlying the path of the chucks and having a discharge opening therein at the feeding point; a rotatable plate in the bottom of the hopper having a series of blank receiving holes therein adapted to register with the discharge opening; means for rotating the plate in synchronism with the movement of the chucks whereby a hole is brought into register with the discharge opening as each chuck enters the feeding point; and mechanism for aligning the chucks with the discharge opening when reaching the feeding point comprising a fixed guide engaging the chucks opposite the feeding point to position same laterally with respect to the orbital path of the series; a disk having notches in its periphery engaging the chucks opposite the feeding point to position same longitudinally with respect to the said orbital path; and means for driving the disk in synchronism with the rotatable delivery plate.

60. 11. In combination with a machine having a series of blank receiving chucks and having means for moving same in an orbital path; mechanism for automatically delivering blanks to the chucks at a feeding point in their orbital path comprising a blank receiving hopper overlying the path of the chucks and having a discharge opening therein at the feeding point; a rotatable plate in the bottom of the hopper having a series of blank receiving holes therein adapted to register with the discharge opening; means for rotating the plate in synchronism with the movement of the chucks whereby a hole is brought into register with the discharge opening as each chuck enters the feeding point; and mechanism for aligning the chucks with the discharge opening when reaching the feeding point comprising a fixed guide engaging the chucks opposite the feeding point to position same laterally with respect to the orbital path of the series; a disk having notches in its periphery engaging the chucks opposite the feeding point to position same longitudinally with respect to the said orbital path; and means for driving the disk in synchronism with the rotatable delivery plate.

65. 12. In combination with a machine having a series of blank receiving chucks and having means for moving same in an orbital path; mechanism for automatically delivering blanks to the chucks at a feeding point in their orbital path comprising a blank receiving hopper overlying the path of the chucks and having a discharge opening therein at the feeding point; a rotatable plate in the bottom of the hopper having a series of blank receiving holes therein adapted to register with the discharge opening; means for rotating the plate in synchronism with the movement of the chucks whereby a hole is brought into register with the discharge opening as each chuck enters the feeding point; and mechanism for aligning the chucks with the discharge opening when reaching the feeding point comprising a fixed guide engaging the chucks opposite the feeding point to position same laterally with respect to the orbital path of the series; a disk having notches in its periphery engaging the chucks opposite the feeding point to position same longitudinally with respect to the said orbital path; and means for driving the disk in synchronism with the rotatable delivery plate.

70. 13. In combination with a machine having a series of blank holding chucks and having means for moving same in an orbital path; mechanism for automatically delivering blanks to the chucks at a feeding point in their orbital path; and mechanism for aligning the chucks with the delivery mechanism at the feeding point comprising a fixed member engaging the chucks opposite the feeding point to position same laterally with respect to the orbital path of the series; a movable member engaging the chucks opposite the feeding point to position same longitudinally with respect to the said orbital path; and means for driving the movable member in synchronism with the delivery mechanism.

75. 14. In combination with a machine having a series of blank holding chucks and having means for moving same in an orbital path; mechanism for automatically delivering blanks to the chucks at a feeding point in their orbital path; and mechanism for aligning the chucks with the delivery mechanism at the feeding point comprising a fixed member engaging the chucks opposite the feeding point to position same laterally with respect to the orbital path of the series; a movable member engaging the chucks opposite the feeding point to position same longitudinally with respect to the said orbital path; and means for driving the movable member in synchronism with the delivery mechanism.

- fixed guide engaging one side of the chucks opposite the feeding point to position same laterally with respect to the orbital path of the series; a cooperating disk having notches in its 5 periphery engaging the other side of the chucks opposite the feeding point to position same longitudinally with respect to the said orbital path; and means for driving the disk in synchronism with the rotatable delivery plates.
- 10 13. In combination with a machine having a series of blank receiving chucks and having means for moving same in an orbital path; mechanism for automatically delivering blanks to the chucks at a feeding point in their orbital path comprising 15 a blank receiving hopper overlying the path of the chucks and having a discharge opening therein at the feeding point; a rotatable plate in the bottom of the hopper having a series of blank receiving holes therein adapted to register with the discharge opening; means for rotating the plate in synchronism with the movement of the chucks whereby a hole is brought into register with the discharge opening as each chuck enters the feeding point; and mechanism for aligning 20 the chucks with the discharge opening when reaching the feeding point, means in the hopper adapted to shift the blanks on the plate outwardly towards the blank receiving holes thereof, said means having a recess permitting surplus 25

blanks in the way of the holes to pass beyond the said means.

14. In combination with a machine having a series of blank receiving chucks and having means for moving same in an orbital path; mechanism for automatically delivering blanks to the chucks at a feeding point in their orbital path comprising 5 a blank receiving hopper overlying the path of the chucks and having a discharge opening 10 therein at the feeding point; a rotatable plate in the bottom of the hopper having a series of blank receiving holes therein adapted to register with the discharge opening; means for rotating the plate in synchronism with the movement of the chucks whereby a hole is brought into register 15 with the discharge opening as each chuck enters the feeding point; and mechanism for aligning the chucks with the discharge opening when reaching the feeding point, means in the hopper between the shifting means and discharge opening 20 adapted to shift the blanks on the plate outwardly towards the blank receiving holes thereof, said means having a recess permitting surplus blanks in the way of the holes to pass beyond the said means, and means in the hopper between the shifting means and discharge opening 25 overlying the holes and adapted to move the passed surplus blanks in way of the holes inwardly towards the center of the plate.

LYSLE J. PULSE.
